UNITED STATES PATENT OFFICE.

HARRY R. IHRIG, OF PERU, ILLINOIS.

TRAFFIC SIGNAL FOR AUTOMOBILES.

Application filed January 2, 1925. Serial No. 87.

This invention pertains to traffic signals for automobiles, and the object is to provide a practical and efficient form of such signal to attach to the headlights of the machine, and embodying right and left turn signals shown on the headlights.

In the drawing—

Figure 1 is a front view of a headlight, the signaling curtain being drawn down in-
10 to operative position;

Figure 2 is a section thru the headlight rim showing the curtain in a lowered position;

Figure 3 is a cross section of a headlight, 15 the curtain being in a raised position;

Figure 4 is a diagrammatic layout of the operating cable and connections.

In combination with the headlights of an automobile, the invention comprises frames 20 1 which are securable in any conventional manner to the headlights 2. Spring rollers 3 are mounted in the upper parts of these frames, and curtains 4 of some suitable transparent or translucent material are attached by their upper ends to these rollers, the lower ends of the curtains being supported by ribs 5 which slide in guides 10 formed in the frame 1 as shown in Figure 3. The curtains 4 have the words "Right" and 25 "Left" suitably lettered thereon, as shown in Figures 1 and 2, the word "Right" being lettered on the right hand curtain, and the word "Left" on the left hand curtain. Small cables 6 are attached by their ends to 30 the ribs 5 and are extended down thru the frames 1 and thru conduits 7 back through the dash 9, and there attached to rings 8 convenient to the hand of the operator. To 35 indicate a right hand turn, the driver pulls the right hand cable, which draws down the curtain at the right hand side, thus showing the word "Right" over that head-

light. Similarly with the left hand cable and curtain to indicate the left turn.

In order to prevent the light rays from 45 the lower reflecting surfaces of the headlights blinding the approaching driver, these surfaces may be finished in a dull finish.

While I have herein described a certain 50 specific manner and method of constructing and assembling the elements of my invention, it is understood that I may vary from the same in minor details, not departing from the spirit of my invention, so as best to construct a practical device for the purpose intended, as defined in the appended claim.

I claim:

In combination with an automobile and a head lamp thereof, an open frame adapted 60 to detachably fit upon the front of the lamp; the said frame having a straight horizontally disposed upper compartment and straight lateral guide ways connecting therewith, the lower half of the frame being 65 semi-circular; a spring shade roller mounted in the said upper compartment; a translucent shade having directional lettering thereupon, mounted upon said shade roller, the lateral edges of the shade being disposed 70 in said guide-ways and the lower edge of the shade being provided with a straight stiffening rib adapted to prevent the downward movement of the shade across the lower semi-circular part of the frame opening; a conduit connected with the lower part 75 of the frame, thence extended downward and then back through the dash of the automobile; and a cable attached by one end to the said stiffening rib at the lower edge of 80 the shade and extended back through the said conduit.

In testimony whereof I affix my signature.

HARRY R. IHRIG,
